UNITED STATES PATENT OFFICE.

HIRAM S. MAXIM, OF LONDON, COUNTY OF MIDDLESEX, ENGLAND.

MACHINE-GUN.

SPECIFICATION forming part of Letters Patent No. 367,825, dated August 9, 1887.

Original application filed May 2, 1884, Serial No. 130,166. Divided and this application filed January 8, 1885. Serial No. 152,245. (No model.) Patented in England February 23, 1884, No. 3,844; in France October 25, 1884, No. 162,735; in Austria-Hungary, November 22, 1884, No. 35,518 and No. 53,930; in Belgium December 30, 1884, No. 66,323; in Italy January 23, 1885, XVIII No. 17,422; in Spain May 19, 1885, No. 4,471, and in Germany September 23, 1885, No. 32,501.

To all whom it may concern:

Be it known that I, HIRAM S. MAXIM, a citizen of the United States, residing in London, England, have invented certain new and useful Improvements in Machine or Battery Guns, of which the following is a specification, reference being had to the drawings accompanying and forming a part of the same, this application being a division of an application filed by me May 2, 1884, No. 130,166.

For this invention I have obtained patents in the following countries and in no others: England, No. 3,844, dated February 23, 1884; France, No. 162,735, dated October 25, 1884; Belgium, No. 66,323, dated December 30, 1884; Germany, No. 32,501, dated September 23, 1885; Austria-Hungary, Nos. 35,518 and 53,930, dated November 22, 1884; Italy, Vol. XVIII, No. 17,422, dated January 23, 1885, and Spain, No. 4,471, dated May 19, 1885.

My present invention relates to improvements in machine or battery guns, the said improvements consisting in a novel construction and disposition of the mechanism for loading, firing, and extracting the shells or cartridges, and in a device for preventing the barrel from becoming heated by rapid discharges of the arm.

The first-named improvements comprise two sets of wheels, which I designate the "feed" and "delivery" wheels. Over the feed-wheel is carried a belt of cartridges, which are transferred to the delivery-wheel by mechanism hereinafter described, and from the delivery-wheel into the barrel by a reciprocating breech-block. The breech-block and the device for transferring the cartridges are connected to a crank provided with mechanism for imparting to it a partial revolution, and the breech-block carries a firing mechanism and extracting device so constructed that by the simple manipulation of the crank all the necessary operations of loading, firing, and extracting are performed in proper order and with great precision and rapidity.

The second part of my invention comprises a water-jacket for cooling the barrel, and a device for permitting the escape of steam, whatever may be the position of the barrel.

My invention also involves certain details in the construction and arrangement of the parts which make up the gun, the nature of which will be more fully hereinafter described.

Referring to the accompanying drawings, Fig. 1 is a longitudinal central section of my improved gun. Fig. 2 is a horizontal section of the same, taken just above the barrel. Fig. 3 is a side elevation of the gear used in the manipulation of the gun, certain parts being removed. Fig. 4 is a sectional view showing the same in detail.

A is a strong metal frame which is provided with a lid or cover, a', and which may be mounted on any suitable stand or carriage.

B is the barrel, and c the breech-block.

D is a crank-shaft, which is carried in bearings D' at the rear part of the frame a.

E is a connecting-rod, one end of which is coupled to the crank-pin D', and the other end of which is coupled to the breech-block c. This connecting-rod is made of such length that when the breech is closed the crank will be nearly or quite on dead-center.

The breech-block C is carried by two cross-heads, C' C'', arranged to slide between suitable guides, F, projecting from the sides of the frame A. The extractor G and the sear H are mounted on the breech-block C, and are acted upon by the double spring G', which is also fixed to the breech-block. The firing-pin I passes through the breech-block C, and is acted upon by a spiral spring, I'', which tends to push it forward. The cock or hammer J is pivoted to a bracket or arm, K, extending downward from the breech-block C, and is made with a circular part, J', which enters a slot, I', in the pin I. The said hammer has, moreover, a curved extension, J'', which, when the breech-block is drawn backward, comes into contact or engagement with a pin or rod, L, fixed in the frame A, so that the said hammer is cocked.

The sear H is a bent lever pivoted to the breech-block, and in its path of movement is a stop, W, which it encounters when the breech is closed by the breech-block, and which sets free the hammer and discharges the piece. The stop W is a pin that extends through a slot in

the frame A, and is adjustable by means of a plate or lever, W', properly secured to the outside of the frame.

Any ordinary device for tripping the sear 5 may be employed; but it is desirable to have some means of shifting the position of the stop, in order that it may be moved out of the path of the sear when it is desirable to close the breech without discharging the gun.

10 The barrel B is fixed to the frame A at B¹⁰. Below the breech is located a feed-wheel, Q, and back of this, with its cartridge-receptacles in line with the bore, is a cartridge-delivery wheel, Q'. The details of the construction and 15 operation of these wheels form a part of the application of which this is a division, and are there fully described. A general understanding of the nature of these parts may be had, however, by reference to Fig. 1.

20 The two wheels Q and Q' contain a certain number of grooves or recesses in line with their axes, and their relative position is such that the uppermost groove of the feed-wheel Q is in line with the lowest groove in the delivery-wheel Q'. These wheels are carried by the 25 shafts Q² Q³, and are provided with the toothed wheels Q⁴ Q⁵, which are geared with each other by means of the intermediate wheel, Q⁶, carried by a stud, Q⁷, fixed to the frame A. The 30 wheels are inclosed in suitable casings, and are rotated by means of a projection or tooth, C⁵, with inclined faces on the breech-block, which engages with teeth or lugs of corresponding shape on the rear portion of the delivery-wheel. By the reciprocation of the 35 breech-block an intermittent rotary movement is thus imparted to the wheels.

A hooked rod, K', is pivoted to the lower end of the bracket K, and when the breech is 40 closed engages with the flange of the cartridge in the uppermost groove of the wheel Q, as shown in Fig. 1. The said rod K' is supported by a spring, K², and is arranged to be acted upon by a fixed arm, K³, having an inclined 45 face which comes in contact with a correspondingly-inclined face on the said rod and depresses the same, and thus disengages it from the cartridge at the proper time.

On one end of the crank-shaft D is a pinion, 50 T. With this engages a toothed segment, U, which is arranged to be partially rotated, first in one direction and then in the opposite, by means of a hand-lever, U', that fits in a socket, U², on the segment, a spring-catch, U³, being 55 used to keep the lever in place. On the end of the crank-shaft opposite to that carrying the pinion T, I fix a boss, T', having a projection, T², which, when the breech is closed, presses against a spring, T³, fixed to the frame A. By 60 these means I prevent the too sudden impact of the breech-block against the barrel. The boss T' and spring T³ are covered by a casting, T⁴.

In order to prevent the barrel from becoming heated by rapid discharges, some means 65 of cooling the same should be used. That

which I employ is a water-chamber, B'', surrounding the barrel, and in order to permit the escape of steam, in whatever position the barrel may be, I place at the side of or above said 70 water-chamber B'' a cylinder, V, which communicates at each end with the chamber B'' by passages V¹ V². The passage V¹ is connected with the forward end of the chamber B'' by means of a pipe, V³. A piston or cylindrical 75 weight, V⁴, is arranged in the said cylinder, and is provided at its ends with the valves V⁵ V⁶. This weight is so arranged that when the muzzle of the gun is elevated the said weight will descend by gravity and the valve V⁵ will 80 close the passage V¹, and when the muzzle of the gun is depressed the said weight will fall in the other direction, so that the valve V⁶ will close the passage V². The steam formed in the chamber B'' will therefore pass into the 85 cylinder V at one or the other end thereof, according to the position of the gun, and the said cylinder is provided with apertures V⁷ to permit the escape of the steam therefrom. The barrel B is held in a stuffing-box, B¹². 90

The operation of the gun is as follows: A belt of cartridges is passed over the feed-wheel Q and the lever U' raised or lowered, as the case may be, to impart a partial rotation to the crank-shaft T. This movement is communicated to the breech-block by the connecting-rod E. The backward movement of the breech-block brings the curved end of the hammer J into engagement with the pin L and cocks the hammer. In its rearward movement the breech-block carries the rod K' back and draws out a cartridge from the uppermost groove of the feed-wheel Q into the lowest groove of the delivery-wheel Q'. At the proper time the rod K' is depressed by the 105 arm K³ and releases the cartridge. It then passes back through the next groove of the wheel Q' to take hold of a fresh cartridge, the two wheels having been moved by the backward movement of the breech-block through 110 the space of one groove. This action is repeated during the time that the gun is in operation. When a shell is brought into the groove in line with the bore, it is forced by the forward movement of the breech-block into the 115 barrel, and at the moment when the breech is closed the hammer is released by the engagement of the sear with the stop W and the cartridge exploded. Then by the manipulation of the lever U' the breech-block is drawn back 120 and the extractor G draws the empty shell from the barrel into the vacant groove of the delivery-wheel. A projection on the extractor G comes in contact with a suitable stop fixed in its path to the frame A and causes the lever to 125 release the shell, which, on the forward movement of the breech-block, is carried by the rotation of the wheel Q off to one side and eventually dropped out of its groove.

The gun which I have now described possesses many advantages, among which are the facility with which it may be fired and the 130

capability of being worked by gunners below it in a protected position.

Without limiting myself to the exact details of construction which I have described, what I claim as my invention is—

- 5 1. In a machine-gun, the combination, with a longitudinally-movable breech-block, a rotary cartridge-holder placed relatively to the breech-block, so that by the forward movement of the latter a cartridge will be forced from the holder into the barrel, and gearing between the breech-block and the cartridge-holder for intermittently rotating the holder in unison with the movement of the breech-block, of a crank-shaft and connecting-rod for imparting a to-and-fro movement to the breech-block, and a device for turning or partially rotating the crank-shaft, all substantially as set forth.
- 10 2. In a machine-gun, the combination, with a longitudinally-movable breech-block, a rotary cartridge-holder placed relatively to the breech-block, so that by the forward movement of the latter a cartridge will be forced from the holder into the barrel, and gearing between the breech-block and the cartridge-holder for intermittently rotating the holder in unison with the movement of the breech-block, of a crank-shaft and connecting-rod for imparting a to-and-fro movement to the breech-block, a toothed segment in gear with a pinion on the crank-shaft, and a lever for operating or turning the segment, all substantially as herein set forth.
- 15 3. In a machine-gun, the combination, with a cartridge-feed wheel, a delivery-wheel, a sliding breech-block arranged to rotate said wheels, and a device connected with the breech-block and adapted to transfer the cartridges from the feed wheel to the delivery-wheel, of a crank-shaft and connecting-rod for imparting a to-and-fro movement to the breech-block, and a hand-lever for turning said crank-shaft, as herein described.
- 20 4. In a machine-gun, the combination, with a cartridge-feed wheel, a delivery-wheel, a

sliding breech-block arranged to rotate said wheels, an extractor and firing mechanism carried by the breech-block, a spring-controlled hooked rod connected with the breech-block and adapted to transfer the cartridges from the feed to the delivery-wheel, a crank-shaft and connecting-rod for imparting a to-and-fro movement to the breech-block, and a hand-lever for operating or turning the crank-shaft, as herein described.

55 5. In a machine-gun of the kind described, the combination, with the sliding breech-block, the crank-shaft, the connecting-rod between the breech-block and shaft, and means for partially rotating the crank-shaft, of the boss T', having the projection T² and fixed to said shaft, and the spring T³, fixed to the stationary frame of the gun, and upon which said projection impinges, in the manner and for the purpose set forth.

60 6. In a machine-gun of the kind described, the combination, with the sliding breech-block, the crank-shaft, the connecting-rod between the breech-block and shaft, and means for partially rotating the crank-shaft, of the boss T', having the projection T², and fixed to said shaft, and the spring T³, fixed to the stationary frame of the gun upon which the projection impinges, and the cover or casing T⁴, secured to the frame of the gun, all as set forth.

70 7. The combination, with the barrel B and a water jacket or chamber surrounding the same, of a separate chamber communicating with the end of the water-chamber, a weight or piston contained in said chamber, valves at each end controlled by said piston, and passages at the ends of the chamber for the escape of steam, all as set forth.

In testimony whereof I have hereunto set my hand this 17th day of November, 1884.
